UNITED STATES PATENT OFFICE.

HENRY C. AMIS, OF STANFIELD, OREGON.

DRAFT-RIGGING.

1,255,683.

Specification of Letters Patent.

Patented Feb. 5, 1918.

Application filed August 15, 1916. Serial No. 115,073.

To all whom it may concern:

Be it known that I, HENRY C. AMIS, a citizen of the United States, residing at Stanfield, in the county of Umatilla and 5 State of Oregon, have invented certain new and useful Improvements in Draft-Rigging, of which the following is a specification.

This invention contemplates an improved 10 draft rigging for railway cars and has as its primary object to provide a construction wherein the draft between the draw bars of the car will be continuous so that when several cars are connected, a continuous draft 15 will be formed from one end of the train to the other.

The invention has as a further object to provide a draft rigging wherein the draft upon a train will be equally distributed between 20 the cars thereof.

The invention has as a further object to provide a draft rigging having a certain amount of slack or give so as to eliminate all jerking or suddenness of motion of the car 25 when a draft is applied thereto.

A still further object of the invention is to provide a continuous draft rigging having an equalizer interposed between the co-acting draw bars thereof and employing an 30 expansion spring which will be compressed by a draft upon either of the said draw bars and will thus act to distribute the draft between the said bars.

And the invention has as a still further object to provide a continuous draft rigging which will relieve the strain upon the center sills of the car and will thus be adapted 35 for use upon cars constructed with wooden bodies.

Other and incidental objects will appear 40 as the description proceeds and in the drawings wherein I have illustrated the preferred embodiment of the invention and wherein similar reference characters designate corresponding parts throughout the several 45 views,

Figure 1 is a fragmentary plan view illustrating the manner in which my improved rigging is supported upon the frame of a 50 car,

Fig. 2 is a longitudinal sectional view of the equalizer employed,

Fig. 3 is a sectional view more particularly showing the construction of the draft 55 members,

Fig. 4 is a sectional view illustrating the arrangement of the followers within the draft members and the springs interposed between the said followers,

Fig. 5 is a sectional view more particularly showing the mounting of the followers, and

Fig. 6 is a fragmentary perspective view of the inner extremity of one of the draw bars and illustrating the connection between the said draw bars and the draft rods of the draft heads.

In order to more clearly illustrate the present invention, I have shown my improved rigging in connection with a portion 70 of a car frame including terminal cross-pieces 10 at opposite ends of the car and between which are arranged spaced parallel center sills 11. Mounted between the said sills adjacent opposite ends of the car frame, 75 are coacting draft members 12 and 13 respectively. These members are substantially identical in construction and each includes a frame or casing comprising confronting side plates or members 14 connected by bolts or 80 other suitable fastening devices 15 to the sills 11. Seating against the bottom edges of the plates 14 is a bottom plate or pan 16 while a top plate or cover 17 is rested upon the upper edges of the said side plates to 85 complete the frame. Connecting the top and bottom plates with the sills, in the manner best shown in Fig. 3 of the drawings, are a plurality of bolts or other suitable fastening devices 18. Projecting inwardly from the 90 side plates 14 adjacent the outer end of the frame, are oppositely disposed stop lugs 19. Similarly arranged stop lugs 20 project from the said plates in inward spaced relation to the lugs 19. Projecting inwardly 95 from the plates 14 adjacent the inner end of the frame, are oppositely disposed stop lugs 21 and similarly arranged stop lugs 22 project from said plates in inward spaced relation to the lugs 21. The frame, is, as best 100 shown in Fig. 3 of rectangular configuration and the plates 16 and 17 may be removed as occasion may demand for gaining access to the interior of the casing of the draft member. Freely mounted within the draft member casing between the stop lugs 19 and 20 is 105 a transversely extending floating follower 23 and freely mounted between the stop lugs 21 and 22 is a similar follower 24. The followers 23 and 24 are provided with oppo-

110

sitely disposed openings through which is freely fitted a stub draft rod 25. Interposed between the followers 23 and 24 is a helical spring or cushioning element 26 which surrounds the draft rod 25 and is fitted at its ends over suitable bosses carried by the said followers. Arranged upon opposite sides of the spring 26 and bearing between corresponding ends of the followers 23 and 24 are helical springs or cushioning elements 27, the ends of which are received by bosses carried by the said followers and as will be observed, the springs 26 and 27 will act to yieldably maintain the followers 23 and 24 in spaced relation.

The inner extremity of the draft rod 25 is screw threaded to detachably receive a turn buckle 28 which confronts the follower 24 and is adjustable upon the said rod to tension the cushioning springs 26 and 27. Slidably connected with the turn-buckle 28 is a draft rod 29 extending longitudinally and inwardly between the sills 11. The stub draft rod 25, at its outer extremity, is formed with a cylindrical head 30 terminating in a squared portion 31 for receiving a wrench so that the said rod may be held fixed to either adjust or detach the turn buckle 28. Freely connected with the head 30 of said rod is a hollow draw bar 32. This bar is, as best seen in Fig. 6 of the drawings, formed at its inner extremity, with an opening 33 through which the head 30 of the rod 25 may be removed for detaching the draw bar from the said rod. Closing the opening 33 is a filler block 34 which is locked in position by a pin 35. The free extremity of the draw bar 32 is formed in any approved manner to couple with a coacting draw bar. The draft members 12 and 13 thus described are arranged to support the draw bars 32 thereof projecting beyond opposite ends of the car frame as particularly illustrated in Fig. 1 of the drawings and interposed between the said draft members to coat therewith, is an equalizer for distributing the draft between the said members. This equalizer is carried by the inner extremities of the draft rods 29 and serves to operatively connect the draft rods. More particularly, this equalizer includes, as best shown in Fig. 2 of the drawings, a plurality of blocks 36, 37, and 38 respectively, the blocks 36 and 37 being slidably mounted upon one of the rods 29 and held against displacement therefrom by a nut 39 while the block 38 is slidably mounted upon the other of the rods 29 and is held against displacement therefrom by a nut 40. The blocks 37 and 38 are recessed to receive the nuts 39 and 40 which are arranged at the inner extremities of the rods 29. Interposed between the blocks 36 and 37 is a helical equalizing and distributing spring 41 arranged to surround the adjacent rod 29 and

fitted at its ends over suitable bosses carried by the said blocks. Detachably connecting the blocks 36, 37 and 38, are coacting rods 42 arranged upon opposite sides of the rods 29 and loosely fitted through the said blocks 70 so that the blocks may slide freely thereon. The equalizer thus described, may, as will be observed, be easily detached from the rods 29 and, if desired, a cross bracket 43 between the sills 11 may be employed for supporting 75 the said equalizer as well as for supporting the inner extremities of the rods 29 in alignment with the stub draft rods 25.

As will now be seen, draft upon one of the draw bars 32, say for instance, the draw bar at the right of Fig. 1 of the drawings, will be communicated from the said draw bar through the draft rod 25 to which it is connected and thence through the adjacent rod 29 to the equalizer, acting upon the 80 block 37 to slide the said block toward the block 36 and consequently compress the spring 41. The draft upon the draw bar 32 at the left of Fig. 1 will, as will be understood, be communicated to the block 38 90 and thence through the rods 42 to the block 36 and compress the spring 41. The spring 41 will, therefore, interrupt the draft between the draw bars of the rigging to distribute the draft between the draft members 12 and 13 and will also provide sufficient play or slack in the rigging to eliminate any jerking or suddenness of motion when draft is applied to either of the draw bars, the said spring being adapted to cushion the draw bars when draft is applied thereto.

In this connection, attention is directed to the function of the draft members 12 and 13. Assuming that a draft is simultaneously 105 applied to the draw bars 32, the compression of the spring 41 of the equalizer will permit the followers 23 and 24 to slide forwardly within the frames of the draft members toward the pairs of stop lugs 19 and 22 respectively. It will now be noted as best seen in Fig. 4 of the drawings, that the followers 24 are normally arranged to engage the lugs 21 while the followers 23 are disposed substantially midway between the 110 pairs of lugs 19 and 20. Consequently, when the followers 23 and 24 are caused to shift forwardly within the frames of the draft members, the followers 23 will first contact with the stop lugs 19 with the followers 24 remaining free. In this position of the followers, draft upon the draw bars 32 will, through the medium of the stub draft rods 25 and turn buckles 28 tend to shift the followers 24 forwardly and compress the springs 27. Consequently, the spring 41 of the equalizer will, as previously described, tend to first cushion the draft, and the springs 26 and 27 of the draft members will then be caused to co-act therewith to 125 130

further cushion the draft and coöperate in eliminating any jerks or suddenness of motion.

As the draft is increased upon the draw bars 32, the followers 24 of the draft members will be moved to engage the stop lugs 22 when a direct pull will then be had upon the draft members. In this connection, it should be noted that the spring 41 of the equalizer is of such length that the said spring may be compressed a distance corresponding to the distance between stop lugs 21 and 22 of both of the draft heads so that the followers 24 of the said draft members may consequently shift to engage the stop lugs 22 for a direct pull upon the draft members.

It will therefore be seen that the draft upon the draw bars 32 will be gradually absorbed by the spring 41 of the equalizer and by the springs 26 and 27 of the draft members. Consequently, load upon the draw bars will, at all times, be effectually cushioned so that there will be no wrenching or jerking of the car frame. I, therefore, provide a construction adapted for use upon cars constructed with wooden bodies since the rigging will relieve any strain upon the center sills commonly employed in connection with wooden bodied cars to receive the draft rigging. As is well known, these sills, when draft appliances as now commonly employed are connected thereto, soon become broken by the jerking and wrenching of the draw bars. It will further be noted that when several cars equipped with my improved rigging are connected, a continuous draft will be provided from end to end of the train formed by the said cars and in this connection, it will be observed that the equalizers of the rigging of the several cars will act to distribute the draft equally therebetween.

When the draft is relieved upon the draw bars 32 as in the case when a car is going down grade, the springs 26 and 27 will act to shift the followers 23 and 24 to their normal position while the spring 41 of the equalizer will again assume its normal position so that when draft is again applied to the draw bars, the rigging will act to effectually cushion the draft. Upon a back thrust against the draw bars 32, the heads 30 of the stub draft rods 25 will shift longitudinally within the said draw bars so that the draw bars will thus act against the followers 23 to shift the said followers inwardly against the springs 26 and 27 of the draft members. Consequently, such backward thrust upon the draw bars will be cushioned by the said springs to eliminate any bumping or jerking of the cars. The extreme inward movement of the followers 23 is defined by the stop lugs 20 arranged to engage with the said followers when the draw

bars 32 will then act directly against the draft members.

Having thus described my invention, what I claim and desire to secure by Letters Patent is:

1. A draft rigging for railway cars including spaced draft members, draw bars associated therewith and arranged at opposite extremities of the car, cushioning elements for the said draw bars carried by the draft members, an equalizer, and means for adjustably tensioning the said elements and operatively connecting the draw bars with the equalizer.

2. A draft rigging for railway cars including spaced draft members, draft rods associated with the said members and arranged at opposite extremities of the car, draw bars connected with the said draft rods, cushioning elements for the draw bars carried by the said members, an equalizer, and means carried by the said draft rods for adjustably tensioning the said elements and operatively connecting the draft rods with the equalizer.

3. A draft rigging for railway cars including spaced draft members, followers carried by the said members, draft rods extending between the followers of the said members respectively and arranged at opposite extremities of the car, draw bars connected to said draft rods, cushioning elements for the draw bars interposed between the followers of the respective draft members, an equalizer, and means adjustable upon the said rods for tensioning the said elements and operatively connecting the draft rods with the equalizer.

4. A draft rigging including a draft member, coacting followers carried by the said member, a draft rod extending loosely between the said followers, a cushioning spring interposed between the followers, means adjustable upon one extremity of the rod to engage one of the followers for tensioning said spring, and a draw bar detachably connected to the opposite extremity of said rod and telescopically fitted thereon to engage the other of said followers.

5. A draft rigging including coacting draft rods and an equalizer connecting the said rods, the equalizer including a block fixed against outward movement upon one of the rods, a block fixed against outward movement upon the other of the rods, a block slidably outwardly upon said second mentioned rod, a rod connecting said last mentioned block with said first mentioned block, and yieldable means interposed between the slidable and fixed blocks of the said second mentioned rod.

6. A draft rigging including coacting draft rods and an equalizer connecting the said rods, the said equalizer including a block connected to the inner terminal of one

of said rods and held against outward movement thereon, a block connected to the inner terminal of the other of said rods and held against outward movement thereon, a 5 block slideable outwardly upon said second mentioned rod, means connecting the fixed block of said first mentioned rod with said slideable block, and a spring surrounding the said second mentioned rod and inter-
10 posed between the fixed block thereof and the said slideable block.

7. A draft rigging for railway cars in-

cluding spaced draft members, draw bars associated therewith and arranged at opposite extremities of the car, draft rods extending from the said bars, cushioning elements for the said draw bars carried by the said members, an equalizer, and turn buckles adjustable upon the said rods for tensioning the said elements and operatively connect- 15 20 ing the draw bars with the equalizer.

In testimony whereof I affix my signature.

HENRY C. AMIS. [L.S.]
